UNITED STATES PATENT OFFICE

111,812

DESIGN FOR A PAPER DRILLING MACHINE

Walter K. Mick, St. Paul, Minn.

Application January 17, 1938, Serial No. 74,353

Term of patent 14 years

To all whom it may concern:

Be it known that I, Walter K. Mick, a citizen of the United States, residing at St. Paul, county of Ramsey, and State of Minnesota, have invented a new, original, and ornamental Design for a Paper Drilling Machine, of which the following is a specification, reference being had to the accompanying drawing, forming part thereof.

Figure 1 is a front perspective view of a paper drilling machine, showing my new design.

Figure 2 is a back perspective view of a paper drilling machine, showing my new design.

The dominant feature of the design resides in the frame of the machine.

I claim:

The ornamental design for a paper drilling machine, as shown and described.

WALTER K. MICK.
